Continuation of abandoned application Serial No. 494,316, March 15, 1955. This application December 5, 1956, Serial No. 627,539

5 Claims. (Cl. 102—28)

The present invention relates to a blasting initiator. More particularly, this invention relates to an electric blasting initiator particularly adapted for mechanical assembly.

This application is a continuation of our prior application Serial No. 494,316 filed March 15, 1955, now abandoned.

Electric blasting initiators are widely used in mining, quarrying, and construction industries and large numbers are produced annually. Essentially, the electric blasting initiators consist of a metal shell enclosing a base charge of a detonating explosive, a priming charge, and an electrical ignition means. The electrical ignition means comprises a burning composition readily ignitable by the heat from an incandescent wire, a high-resistance bridge wire imbedded in the burning composition, and a pair of leg wires leading from outside the metal shell and connected within the shell by means of the bridge wire. The leg wires are maintained in a parallel spaced relationship within the shell by a plug sealing the open end of the shell. This plug, or some element associated with the plug, must hold the leg wires with sufficient firmness so that they will not be pulled out of the shell during normal handling, nor will they be moved sufficiently to break the bridge wire connection or to produce a short circuit with each other or the shell wall. The bridge wire is imbedded in the burning composition either by introducing the leg wire-bridge wire assembly into a shell containing a loose ignition charge until the bridge wire is surrounded by this loose charge, or by incorporating a binder with the ignition compositions and applying the composition in the form of a bead to the bridge wire and thereafter introducing the beaded assembly into the shell.

In the past, the electric blasting initiators have been assembled primarily by hand, and the assemblers exercised considerable caution and skill to prevent breaking the bridge wire during the assembly operation. Also, in the case where the leg wire-bridge wire assembly is introduced into a loose mass of powder, the assemblers exercised judgment in positioning the assembly so as to avoid defective assemblies due to irregularities in either the shell length or the height of the loose powder within the shell. For example, if the bridge wire is pressed beyond the loose powder portion, it may be broken by contact with the unyielding pressed charge. On the other hand, if the bridge wire is not introduced sufficiently to be imbedded, in the loose ignition composition, no initiation may occur when a current is applied.

At present, the assembly of initiation devices by mechanical means instead of hand means is of growing importance. Therefore, it is desirable to provide an electrical blasting initiator design wherein the exercise of caution and judgment during assembly is not a requirement.

The same construction features are found in electric delay blasting initiators, wherein a delay train is posi-

tioned between the electrical ignition means and the priming charge, and the same problems regarding mechanical assembly exist as in the case of the regular electric blasting initiators.

5 Electrical blasting initiators are frequently used in areas where only the current produced by conventional blasting machines is available, and in many cases, a large number of the initiators connected in series or in parallel are preferably initiated simultaneously. Therefore, the ignition means should function when only a small current (for example, 0.5 ampere or less) is applied. On the other hand, the initiators are frequently used in areas where high voltages (440 volts) are used to power equipment and to initiate the blast. When a high voltage current is applied to an electrical initiator, an arc may be formed which will pierce the shell walls. In the case of delay initiators, such piercing may interfere with the functioning of the delay train. Therefore, the ignition means should function when a high voltage power source is applied, and, in the case of a delay initiator, the formation of an arc should not render the initiator ineffective. In many field areas, initiators are exposed to very high voltage static discharges. The initiators should not be initiated by the influence of such discharges. Therefore, a preferred electric blasting initiator should be resistant to static discharges, be resistant to high voltage arcing damage, and yet be ignitable by the application of a relatively small current.

30 Accordingly, an object of the present invention is to provide an electrical blasting initiator adapted for mechanical assembly. Further, an object of this invention is to provide an electrical blasting initiator which has excellent static resistance. A still further object of this invention is to provide a delay blasting initiator which will not be rendered ineffective by the formation of an arc. Additional objects will become apparent as this invention is more fully described.

35 The foregoing objects are attained by providing an electric blasting initiator having an elongated ventless tubular metal shell, a base charge of a detonating explosive within said shell, a priming charge adjacent to the base charge, and an ignition assembly comprising a rigid cup-shaped capsule of a non-metallic composition, said capsule having a larger diameter at the open end than at the closed end and side walls of greater thickness than the bottom wall thereof, and ignition composition substantially filling said capsule, a bridge-wire embedded in said ignition composition and connecting a pair of leg wires, and a plug of insulating material completely surrounding said leg wires, said plug having its base flush with the top of said capsule and said capsule being prevented from inward movement within said shell by a peripheral crimp in the sidewalls of the shell. Delay initiators will include a delay train interposed between the ignition assembly and the priming charge.

40 In order to more fully describe the initiator of the present invention, reference is now made to the accompanying drawing in which:

Figure 1 represents a cross-sectional view of a blasting cap of the present invention containing a delay carrier.

Figure 2 is a cross-sectional view of the plastic capsule contained in the blasting cap of Figure 1.

Figure 3 is a cross-sectional view taken along the line 3—3 of Figure 1, and

Figure 4 is a cross-sectional view of a regular, non-delay cap of the present invention.

Throughout the several views, like numerals represent like parts.

45 In the drawing, 1 is an elongated tubular shell, for example, of gilding metal or aluminum, 2 is a base charge of a detonating explosive, for example, tetryl, cyclonite,

or pentaerythritol tetrinitrate, 3 is a priming charge, for example, lead azide or mixtures of lead azide and a bis-basic salt of lead nitrate with a nitrophenol, 4 is a delay train carrier, for example, lead or synthetic plastic tubing, 5 is a delay charge, for example, an 85/15 barium oxide/selenium mixture or 2/98 boron/red lead mixture, 6 is a peripheral crimp in the shell wall which prevents the delay train carrier 4 from damaging the ignition assembly in the event it is jarred loose, 7 is an ignition composition, for example, a 50/25/25 smokeless powder/potassium chlorate/dibasic lead salt of a nitro-phenol mixture or a 2/98 boron/red lead mixture, 8 is a nonmetallic capsule, for example, of molded polyethylene or nylon, 9 is a peripheral crimp in shell 1 supporting capsule 8 having a continuous side wall 8a of substantial thickness compared to a very thin bottom wall 8b, 10 is a bridge wire imbedded in the ignition composition 7 and connecting leg wires 11, 12 is a mechanically assembled plug of a rubber-like composition preformed into two halves and held together prior to insertion into shell 1 by means of metal ferrule 13, 14 is a groove through the plug, 15 is a beaded portion on leg wires 11, and 16 are crimps in the wall of shell 1 which hold plug 12 firmly in position.

In the assembly of the initiator depicted in the drawing, base charge 2 is first introduced into shell 1, and pressed with a pin which produces the hollow to be filled with priming charge 3. The priming charge 3 is then loaded into shell 1 and pressed into position, after which delay carrier 4 containing delay composition 5 is pressed into shell 1. The length of the delay train and the nature of composition 5 determine the period of delay. Peripheral crimps 6 and 9 are next formed. Capsule 8 is then pressed into shell 1 until seated on the inward projection formed by crimp 9, after which ignition composition 7 is introduced in loose form. The mechanically assembled plug 12, including leg wires 11 and bridge wire 10 is introduced into shell 1 and pressed in until the bottom is flush with the top of capsule 8. Peripheral crimps 16 complete the assembly. If a regular initiator is being assembled, the delay carrier 4 and delay composition 5 are omitted, and a considerably shorter shell 1 is used.

When an electric current is applied to the initiator of the present invention, bridge wire 10 becomes incandescent, igniting composition 7. The rapid combustion of the ignition composition 7 pushes out the thin bottom 8b of capsule 8, sending a hot, short duration flash to the top of delay composition 5 or to the priming charge 3 if the initiator does not contain a delay train. The delay composition 5 burns essentially without the evolution of gas and the heat of combustion is transmitted through the composition 5 to priming charge 3, which is thereby ignited and in turn detonates base charge 2.

In the event the initiator of the present invention is exposed to stray currents (static), the capsule 8 serves to insulate the portion of the leg wires 11 surrounded by ignition composition 7 so that no spark can jump from the leg wire to the wall of shell 1 at this point and prematurely ignite the composition 7. In the event excessive current is applied so that an arc is formed, the groove 14 in alignment with the beaded portions 15 of leg wires 11 provides a path for the arc and the wall of shell 1 is pierced, if at all, only above a portion of plug 12 and the necessary confinement for effective combustion of the delay composition 5 is retained.

From the foregoing description, it is apparent that variations in the length of the shell, the length of the delay train, the height of the pressed charges, etc., will not have a deleterious effect on the assembly of the ignition means. This is particularly important in the case of delay initiators of the ventless type because the amount of ignition composition which can be used is limited. If too much ignition composition is included, the shell may be burned through, thus removing the confinement needed for accurate burning of the delay composition, or, in

some cases, the shell may even be burst by the presence of too much ignition composition.

The improved resistance to the effect of static is illustrated by the following test results. In the test, initiators containing base charges, priming charges and delay charges of the same kind and weight were provided with identical loose ignition mixtures comprising boron and red lead around the bridge wire. A spark current from a charged condenser was passed simultaneously through both leg wires to the grounded metal shell of the initiator with the bridge wire in place.

The initiators tested were as follows:

- A. As shown in the drawing, using a molded polyethylene capsule.
- 15 B. Similar to A, except that the plug contained no transverse groove.
- C. A standard delay initiator having no capsule, and no transverse groove in the plug.

	Type	The minimum energy in joules required to fire any one of ten detonators
25 A		0.16
B		0.08
C		0.0012

It is apparent from the foregoing table that the presence of the capsule produces a tremendous improvement in static resistance, and that the addition of the transverse groove in the plug increases this resistance by 100%.

The initiators of the present invention were also tested for the effect of arcing when they were fired singly by the application of a 440 volt current. Those having plugs without the groove were erratic in their delay periods, and in several instances failed to fire. Those having the plug with a transverse groove consistently fired at the specified delay interval.

As will be seen from the foregoing, the use of a mechanically assembled plug having a transverse groove in delay initiators is a preferred form of the present invention. However, the tests with the plug which did not contain such groove show that the presence of the groove is not essential for effective reduction of static sensitivity nor will the absence of the groove affect the assembly of initiators. Therefore, the use of a plug in which no transverse groove is present is included within the scope of this invention.

The use of a plug prepared by assembling preformed halves is advantageous from a mechanical assembly standpoint, particularly when a transverse groove is desired. Other well-known methods of forming plugs to seal initiators and to retain the leg wires in position can be used without departing from the spirit of this invention.

- 55 The use of a plug-shaped capsule having sidewalls of greater thickness than the bottom wall and having a contour such that the inner diameter at the top is greater than the diameter at the bottom is a critical feature of this invention. The reduced thickness of the bottom wall causes the flash from the ignition composition to be directed on the priming charge or the delay composition rather than toward a side wall of the shell. Tests have shown that a bottom wall thickness of more than about 0.012 inch is undesirable because the ignition composition may not flash through the heavier walls. If the sides are tapered they will tend to insure proper seating of the capsule on the inward projection formed by the peripheral crimp. The thick sidewalls also provide sufficient rigidity to the capsule to prevent collapse when the plug is pressed into the shell.
- 60 The capsule is of a nonmetallic composition in order to provide the desired insulating characteristics. Preferably, the capsule will be fabricated from a thermoplastic or thermosetting synthetic composition such as polyethylene or nylon, although materials such as wood or paperboard can be used.

- 70
- 75

The present invention has been described in detail in the foregoing. We intend, however, to be limited only by the following claims.

We claim:

1. An electric initiator adapted for mechanical assembly comprising an elongated tubular metal shell, a base charge of a detonating explosive at the bottom of said shell, a priming charge adjacent to said base charge, a peripheral crimp in said shell above said base and priming charges to prevent said charges from undue shifting in the event they are jarred loose, a second crimp in said shell above said first-named crimp, a rigid cup-shaped capsule of non-inflammable plastic supported in an upright position by said second crimp, said capsule having a substantially larger inner diameter at its open upper end than at its closed lower end and having side walls of substantially greater thickness than its base, an ignition composition within said capsule, a bridge wire connecting a pair of leg wires embedded within said ignition composition, and a plug of insulating material surrounding and supporting said leg wires, the base of said plug lying flush with the top of said capsule whereby an electric current impressed across said leg wires will heat the bridge wire to incandescence and initiate the ignition composition with a downward flash directed toward the base and priming charges.

2. A device as in claim 1 wherein the leg wires are each provided with an anchor portion of enlarged diameter at an intermediate point and the plug has a transverse groove in which the enlarged anchor portions of the leg wires are seated.

3. An electric initiator adapted for mechanical assembly comprising an elongated tubular metal shell, a base charge of a detonating explosive at the bottom of said shell, a priming charge adjacent to said base charge, a delay train having a delay charge above said priming charge, a peripheral crimp in said shell above said delay train to prevent said delay train from undue shifting in the event it is jarred loose, a second crimp in said shell above said first-named crimp, a rigid cup-shaped capsule

of non-inflammable plastic supported in an upright position by said second crimp, said capsule having a substantially larger inner diameter at its open upper end than at its closed lower end and having side walls of substantially greater thickness than its base, an ignition composition within said capsule, a bridge wire connecting a pair of leg wires embedded within said ignition composition, and a plug of insulating material surrounding and supporting said leg wires, the base of said plug lying flush with the top of said capsule whereby an electric current impressed across said leg wires will heat the bridge wire to incandescence and initiate the ignition composition with a downward flash directed toward the base and priming charges.

15 4. An electric initiator adapted for mechanical assembly comprising an elongated tubular metal shell, a base charge of a detonating explosive at the bottom of said shell, a priming charge adjacent to said base charge, a crimp in said shell above said priming charge, a rigid cup-shaped capsule of non-inflammable plastic supported in an upright position by said crimp, said capsule having a substantially larger inner diameter at its open upper end than at its closed lower end and having side walls of substantially greater thickness than its base, an ignition composition within said capsule, a bridge wire connecting a pair of leg wires embedded within said ignition composition, and a plug of insulating material surrounding and supporting said leg wires, the base of said plug lying flush with the top of said capsule whereby an electric current impressed across said leg wires will heat the bridge wire to incandescence and initiate the ignition composition with a downward flash directed toward the base and priming charges.

20 5. A device as in claim 4 wherein the leg wires are each provided with an anchor portion of enlarged diameter at an intermediate point and the plug has a transverse groove in which the enlarged anchor portions of the leg wires are seated.
